(57) **CLAIM**

What is claimed is the ornamental design for a fan, as shown and described.

DESCRIPTION

FIG. 1 is a perspective view of a fan, showing the new design in a deployed configuration;

FIG. 2 is an enlarged right-side elevational view thereof in a straight configuration;

FIG. 3 is an enlarged left-side elevational view of FIG. 2;

FIG. 4 is an enlarged rear elevational view FIG. 2;

FIG. 5 is an enlarged front elevational view FIG. 2;

FIG. 6 is an enlarged bottom plan view FIG. 2; and,

FIG. 7 is an enlarged top plan view FIG. 2.

The broken line showing of a hookah is included for the purpose of illustrating environmental structure and forms no part of the claimed design.

The neck of the fan has been shown broken-away to indicate indeterminate length.
